UNITED STATES PATENT OFFICE.

WILLIAM E. ELLIOTT, OF GRAND RAPIDS, MICHIGAN.

SHOE-BUTTON.

1,208,934.

Specification of Letters Patent. Patented Dec. 19, 1916.

Application filed March 21, 1916. Serial No. 85,609.

To all whom it may concern:

Be it known that I, WILLIAM E. ELLIOTT, a citizen of the United States of America, residing at Grand Rapids, in the county of Kent and State of Michigan, have invented 5 certain new and useful Improvements in Shoe-Buttons; and I do hereby declare the following to be a full, clear, and exact description of the invention, such as will enable others skilled in the art to which it appertains to make and use the same.

This invention relates to a button construction especially adapted for use in shoe buttons in which an attaching loop or eye 10 is permanently secured to and projects from the underside of the button.

It is the object and purpose of my invention to provide a construction in which a shoe button having a head formed of pearl or like comparatively fragile material, may be equipped with an insert of different material in its under side, whereby the completed head may have a downwardly projecting neck of circular outline, the sides of 25 which curve upwardly and outwardly from the lower end of the neck to meet the under sides of the main body of the head. In the manufacture of pearl buttons it is substantially impossible to form, in any practical 30 manner, a completed head and neck of this description entirely of pearl or the like. My invention permits the formation of a button having all of the functions of a button of this character yet which so far as any portions 35 of the button disclosed in use are concerned will show only the pearl or like material.

A further object of the invention consists in the provision of means for attaching the 40 head and the insert together, this attachment being effected by securing the loop or eye to the button head.

Other objects and purposes of the invention will appear with understanding of a 45 preferred embodiment thereof as disclosed in the accompanying drawing, in which:

Figure 1 is a vertical section taken centrally through a shoe button made in accordance with my invention. Fig. 2 is a similar 50 section taken through the button at right angles to the section illustrated in Fig. 1. Fig. 3 is an under plan view of the shoe button. Fig. 4 is a perspective view of the insert and the attaching loop; and Fig. 5 is 55 a perspective view of a plug which is inserted in the upper side of the button head.

and connected to the ends of the wire forming the attaching loop.

Like reference characters refer to like parts throughout the several views of the 60 drawing.

The head 1 of the button is of pearl or similar material and has a central opening therethrough, the upper end of which has diverging sides 2. On the underside the 65 head 1 is bored to form a circular recess 3, the center of which is coincident with the axis of the opening through the head. An insert comprised of a body 4 of circular outline and a downwardly projecting neck 5 is 70 formed of any suitable material. In practice this material will be any regular button material such as papier-mâché or the like and the neck has upwardly and outwardly curved surfaces extending from the lower 75 end of the neck to the points where it meets the under surface 7 of the head 1, the thickness of the body 4 being such that a smooth and unbroken surface is presented at the juncture of the insert and the head 1. 80

The underside of the insert is slotted for a distance as shown at 8 to form a seat for the upper part of a loop 9, this loop being formed of wire, the ends 10 of which are brought together, passed through the insert 85 and into the lower end of the central opening in the head 1. A plug comprised of a conical head and a cylindrical extension 12 is passed into the opening from the upper end, its lower end meeting the upper ends 90 of the wires 10 and is permanently secured thereto, preferably by electric welding, it being evident that when so connected the loop, head and insert are permanently secured together making a complete button 95 which has a head of pearl or like material, a neck of any other suitable material which may be readily fashioned into the form desired and a loop depending from the neck together with a metal head centrally located 100 in the upper side of the head which greatly adds to the appearance of the button when in use.

A head of the character defined may be readily formed from pearl or like material. 105 The insert and loop may be formed together at one operation and the combined insert and loop added to the head and readily secured thereto in the manner described. Furthermore the permanent connection of the 110 plug and loop permits the employment of steel or like durable material for the loop

which heretofore it has been practically impossible to use in this relation.

The finished button presents a pleasing and attractive appearance and the neck of 5 novel formation added to the head gives the button all of the many advantages fully set forth in my previous application Ser. No. 55,219, filed Oct. 11, 1915.

I claim:

- 10 1. A button comprised of a head having an opening therethrough and a recess in its underside, a loop formed of a piece of wire having the ends thereof brought together and inserted into said opening at one end, 15 an insert through which said ends pass seated in the recess in the head and a plug inserted into the opening at the other end and connected with said ends of the loop, substantially as described.
- 20 2. A button comprised of a head having an opening therethrough and a recess in its

underside, an insert seating in said recess, a loop formed of a piece of wire having the ends brought together and passed through said insert and into the opening in the head, 25 and means for permanently connecting the loop and the head, substantially as described.

3. A button comprised of a head having an opening therethrough and a circular recess in its under side, an insert comprised 30 of a body and a downwardly extending neck provided with downwardly and inwardly curving sides, said body being received within the recess of the head to provide a smooth and unbroken surface from the neck to the head, and a wire loop projecting from the underside of the insert, said head, insert and loop being permanently connected together.

In testimony whereof I affix my signature. 40

WILLIAM E. ELLIOTT.
